UNITED STATES PATENT OFFICE.

HEINRICH KARL, OF JERSEY CITY, NEW JERSEY.

PORTABLE TRIP DEVICE.

Application filed March 24, 1924. Serial No. 701,455.

This trip-device serves for the operation of a vent-device and other devices on the train in the well known manner which causes the stopping of the train. Trip-devices of all kinds of shapes beside the rails are well known and some forms of such devices are used extensively, but they are all designed with the understanding that they are not to be voluntarily taken away again after they have stopped a train. The novel feature in this invention resides therefore in that one or several whole trip-devices are carried by each train and that such trip-devices may also be kept in reserve at any station, at switch towers, gates, crossings, etc., and that they are so constructed and of a comparatively light weight so that they can be easily carried by a person in charge and quickly put in place beside the rail at any desirable point along the railroad-line and taken away again at any time.

Supposing a train has some mishap or disaster and is thereby compelled to stop for a longer time than usual at a point of the railroad-line where another train, perhaps of high speed, is to follow closely; it usually has been customary to send a flagman to a certain distance in the rear and have him wave the red flag or have him place a fusee at that point to signal the approaching train of the presence of another train. This method of signalling may not, however, suffice to stop the rear train because the flagman or the fusee may not be noticed by the engineer of the rear train, as has actually been proven in some cases, or the signal may be perceived only too late. It is therefore of greater value to have a device at hand whereby the train from the rear will be stopped regardless of the actions and intentions of the engineer of said train. It is understood that each train must possess the venting device which in a well known manner operates to cause an emergency or service stop of the train. For causing a gradual diminution of the speed and a smooth stop, however, such arrangements may be made on the train which are shown in the copending Patent applications S. Nos. 314,588 and 349,715, filed July 31, 1919 and January 6, 1920 respectively, of which I am co-applicant; or which are shown in my copending Patent application S. No. 652,581, filed July 19, 1923. These applications illustrate and describe automatic train control systems.

In the drawings—

Figure 1 is a diagrammatic view illustrating an application of the present invention;

Figure 2 is a front view of another form of trip device;

Figure 3 is a side elevation thereof;

Figure 4 is a transverse section of still another form of trip device;

Figure 5 is a side elevation of the form shown in Figure 4;

Figure 6 is a transverse section of still another form of the trip device;

Figure 7 is a view illustrating a slight modification of the construction shown in Figure 4; and

Figure 8 is a diagrammatic view of a locomotive, showing the parts carried thereby which cooperate with the trip device.

A practical arrangement would be that the tripping device that is to be carried easily from a train that is stalled at some point along the road-side be so constructed that it can be affixed to a part of the track and after it is affixed beside or to the rail need no further attendance by a person except for its removal. The tripping-part of this device must be sufficiently yieldable so as to incline when the engine-plough pushes it, and must have enough resistance to push the lever 17 of the vent-valve and other levers on the engine. Such trip-devices are illustrated by Figs. 2 to 7, and one of these devices is supposed to be employed in Fig. 1 and placed at the point indicated by 11.

These devices when once affixed do not need the further attention of the person in charge except for their removal after the oncoming train has been controlled. The person in charge, then, may go still further to the rear at the point 12 and signal the next oncoming train to stop its progress. If such signals should not be seen or not observed, the stopping of the oncoming train 18 will be obtained shortly after the lever 17 is operated by the trip-device, and thereby a collision with the stalled train is avoided. In certain circumstances it may become necessary for a stalled train to protect itself by

means of more than one portable trip-device, as for instance when the train is compelled to stop at a point where one or several other railroad-lines cross or when it is a single railroad-line with traffic in both directions. In the latter case the stalled train should be protected by portable trip-devices that are placed a certain distance ahead of the train

115

and a certain distance in the rear of the train. It is therefore advisable for each train to carry several of these portable trip-devices, and for more than one of the train-crew to have charge of affixing them whenever it is necessary.

If the engine is an electrically propelled one, the electric current that is employed for propelling the train may be cut off by the operation of a lever that is arranged in a level-line and vertical plane similar to the lever 17. An example of such a device is shown in Figs. 2 and 3. It is shown there that an electric contact 38 becomes separated from two contacts 39, 40 when the lever 41 is operated by the tripping-part of the portable trip-device. Similar arrangements are well known in the art and are also employed in the aforementioned co-pending Patent applications, Serial Nos. 314,588, 349,715 and 652,531, of which I am co-applicant or sole applicant respectively.

In Figs. 2 to 6 there are shown modifications of the device which include a clamp-like part that is to be placed on the head of the rail. This arrangement is especially suitable for railroads on which the part on the left of the rail 1 (according to Figs. 2 and 4) is filled up with earth or stones or concrete, etc.

The clamp-like part is indicated by the reference numeral 56. This clamp-like part 56 consists of a top portion that is to lie on top of the rail and is made of a relatively thin hard metal sheet over which the wheels of the train must roll. There are (preferably two) flanges 57 which depend from the part 56 on opposite sides of the rail that may be somewhat flexible to allow this part to be pressed on the railhead and to hold there sufficiently when some obstruction on the train is pushing the tripping-part 58 or 58' that is constructed to allow a certain give. These flanges 57 may be thinner toward their lower edges to permit the flexibility thereof.

In Fig. 4 there is an addition shown which consists of a device that permits the better holding of the clamp-like part 56 to the rail-head and consists first of a portion 59 that is added to the flange 57 that is to come in alignment with the inner side of the rail 1. This portion 59 has a hole 60 which has a screw-winding 61 and a regular screw may be set in there to screw on the part 56 tightly. In the form shown in Fig. 4, however, there is a pin 62 employed which has only a short screw-winding 63 near the pin head 64. With this kind of pin it is not necessary to turn as long as would be necessary when the screw-winding was extended over the whole length of the pin to reach the rail wall 1'. In the example shown in Fig. 4 the pin 62 needs simply to be pushed in until the winding 63 comes in touch with the

winding 61 and it is only then that the pin is to be turned until the front part touches the rail wall 1' immediately under the rail-head. For taking off the part 56 from the rail-head the pin 62 simply is to be turned in the opposite direction, as with screws, until the somewhat thinner portion 62 of the pin can be simply pushed through the hole 60; that is, until the somewhat thickened front part is situated in the wider part of the hole 60. United with the flange 57 that is to come in alignment with the outside wall of the rail-head is a part 65 with a hole in which a screw-winding 65' is provided that fits to the screw-winding of the shaft 66 which forms the base part of the tripping-part 58 of the device of Fig. 4. In Fig. 5 it is indicated how the stop 67 and the spring 68 are arranged to hold the tripping-part 58 in vertical position. For adjusting and securing the stop 67 and the spring 68 the part 65 is thickened on one side and provided with square holes 69 and 70. The stop 67 which on that respective part is angular to fit in the square of the hole 69 is thereby held sufficiently rigid, and also the spring 68 is made angular to hold rigidly in the hole 70 that is square. The spring 68 is a simple strong wire of flexible steel; it can be as well a coiled spring or a leaf-spring, and the affixing thereof may be different from that shown in Fig. 5.

Referring more particularly to the modification of Fig. 6, the parts thereof are all similar to those shown in Fig. 4 except that the fastening device of the part 59 and the pin 62 is not employed on the border 57 of the clamp-like part 56, and that the tripping-part 58' is connected to the respective part 65'' of the clamp-like part 56 in a way that is different from that shown in Fig. 4. In the modification of Fig. 6 the shaft 66' is provided with a thickened end 71 which is revolvably inserted in the hollow provided for in the part 65'' and this hollow is so shaped to fittingly hold said shaft 66' so that it cannot be separated from the part 65'' except when the upper portion of 65'' is taken off by unscrewing it from the lower part thereof.

In Fig. 7 a form of tripping-part is shown which in its construction is similar to the tripping-part of the device shown in Figs. 2 to 6 as far as it concerns the upper portion of the tripping-part. The difference between the device of Fig. 7 and those of Figs. 2 to 6 consists in that the tripping-part shown in Fig. 7 has a downwardly directed extension 72 to which a weight 73 is fastened and so adjusted that it will touch the rail-base when the tripping-part is in its vertical position whereby it is provided that the tripping-part does not swing like a pendulum when hit by an obstruction on the train.

According to Figs. 2, 3 and 7, the part 65 is situated above the level-line of the top portion of the part 56, while the device of Figs. 4, 5 or 6 shows the part 65, 65'' respectively in a lower level-line so that the top of 65, 65'' is situated in the same level-line as the top of the part 56, which is more advantageous because there is less possibility of breakage when the wheels of the train roll over the part 56.

It is understood that instead of the tripping-levers 58 or 58' a ramp may be employed and springs may be arranged between the base-part and the ramp to allow the latter to have some give when hit by an obstruction like the plough of the engine. As the weight of the device would, however, be increased if a ramp were employed instead of one of the illustrated tripping-parts, the latter seem to be preferable.

Having described my invention, I wish to make it understood that there may be many additions or changes possible without however departing from the spirit and scope of the invention.

I claim:

1. A portable trip device for controlling the operation of braking mechanism of a train, including a plate capable of resting upon the tread of a rail and having depending flanges engageable with the sides of said tread, one of said flanges having a bearing depending below the tread of the rail, a retaining member adjustable in said bearing and engageable with the web of the rail directly beneath the tread thereof, a bushing extending from the other depending flange, and a trip arm threaded in said bushing.

2. A portable trip device for controlling the operation of braking mechanism of a train, including a plate capable of resting upon the tread of a rail and having depending flanges engageable with the sides of said tread, a bushing extending from one of said flanges, a trip arm having a laterally extending shaft rotatable in said bushing, and a spring member carried by said bushing and engageable with said trip arm to yieldably maintain the arm in a vertical position.
